PUSH-BROOM-TYPE VACUUM CLEANER

Original Filed April 27, 1932

INVENTOR
W. Leathers

UNITED STATES PATENT OFFICE

2,187,164

PUSH-BROOM-TYPE VACUUM CLEANER

Ward Leathers, Haworth, N. J., assignor to
Quadrex Corporation, New York, N. Y., a corporation of Delaware

Original application April 27, 1932, Serial No.
607,781. Divided and this application January
21, 1937, Serial No. 122,196

3 Claims. (Cl. 15—16)

The object of my invention is to produce a suction floor cleaner for serving a multiplicity of cleaning purposes in the highest conceivable manner and with the least weight and trouble.

This application is a division of my application for Letters Patent, Serial No. 607,781, filed April 27, 1932, now Letters Patent 2,072,892, issued March 9, 1937.

In order to set forth my invention so that all those familiar with these arts may understand it, I have prepared the following specifications to which I have appended a drawing, of which:

Figure 1 shows my complete floor cleaner partially sectioned.

Figure 2 shows a cross-section of the motor-suction-unit, filter, and dirt receptacle.

The normal floor line 1 shows a cleaner in its normally used position. The floor line 2 in dotted lines shows the machine in use in a position horizontal with the floor. 3 is a motor-suction-unit shown in dotted lines. 4 is an outside casing for same joined to the blower casing 5 by screws. 6 is a removable dirt-receptacle. A filter tube 7 is surrounded by a filter casing 8, provided with outlet ports for filtered air 9 and joined to the outside casing 6 as by screws. A handle tube 10 is shown rigidly attached to the casing 8. A cord is provided at 11. A rubber bumper 12 is useful in case the machine is dropped on the floor.

Figure 2 shows the motor and blower of the motor-suction-unit, the filter, and dirt receptacle assembly in cross-section. 13 is a motor mounted on suitable bearings in the casing member 4. 4 is shown as a die casting wherein the side walls of the inner motor housing and the outer motor housing are in one die casting. This same casting has a back wall 15 for the air passage 16 which leads to the filter. Clean air leaking in around the dirt-receptacle 6 is drawn into the motor at 20 by a motor ventilating fan 21, through a baffle plate 22, and exhausted at the port 23. The motor 13 drives a main suction fan 25 which has a spillway around its periphery into the chamber located between the inner and outer walls of the part 4. The spring 26 holds the receptacle 6 in engagement with a groove 27 in the part 4, which part has been so designed for die casting purposes that it has integral with it a ring member 28 to which the filter is attached and to which the filter cover 8 is also joined as by screws. The filter 7 is made of a cylinder of light, tightly woven, porous material. It has an annular top 29 suitably gored and sewn. 29 is sewn on its periphery to the

upper edge of the cylinder 7. An inner piece of fabric 30 (shown in cross-section) is joined to the cylinder 7 by sewing along two sides, leaving an opening at the top 31 over which the dirt-laden air from the main suction fan 25 disposes 5 of the dirt. The part 30 thus forms, together with the side wall of 7, a tubular passage, the lower end of which is joined to the die casting 4 by means of a spring clip 32 which fits in a suitable opening. The rim of the cylinder fabric is joined 10 to 4 by a wire or ring 33 or other suitable attachment. A wire rod 34 suitably supported from the part 4 passed up at the outside of the filter and supports it by being tied thereto at 35. 15

I claim:

1. In a suction cleaner, the combination of a filter unit, a dirt-laden air duct-connector, and a motor-suction-unit all in rigid interconnected longitudinal arrangement with the filter unit at the top of the cleaner, the said air-duct in the 20 middle but at one side and wholly between the filter unit at the top and the motor-suction-unit at the bottom, an upwardly impinging spring joined to the top of said motor-suction-unit and a ring member joined to the top of said duct-connector, said combination surrounding on three sides a manually removable dirt receptacle 25 being substantially cylindrical in form and having a diameter substantially that of the motor-suction-unit, a rigid ventilated cylindrical filter- 30 cover surrounding a cylindrical filter, joined to the top of said connector and said ring member and supporting an operator's handle at the top, said receptacle making a substantially air-tight juncture with said ring member when 35 held upward by said spring, the said combination of parts making a substantially annular structure supportable on a floor nozzle connectable with the motor-suction-unit. 40

2. In a suction cleaner, a motor-suction-unit, 45 a casing for said motor comprising an inner sleeve holding said motor and an outer substantially concentric portion constituting a chamber through which dirt-laden air is delivered by the fan of said unit, said outer chamber being extended upwardly by means of walls parallel with the motor axis but at the side thereof, an upwardly impinging spring joined to the top of said motor-suction-unit and a ring member joined to the top of said duct-connector, a sleeve-like filter, 50 the lower end of which provides communication with the said chamber extension, a substantially cylindrical rigid filter-cover surrounding said filter and joined at the lower end to the aforesaid upwardly extending portion of the ex- 55

haust chamber and said ring member, a handle for operating the cleaner mounted on the upper end of the rigid filter-cover, a removable dirt receptacle at the side of said upwardly extended section in communication at its top with the bottom of said filter, said receptacle making a substantially air-tight juncture with said ring member when held upward by said spring and with all said parts forming a substantially annular and concentric unit substantially coaxial with the motor.

3. In a suction cleaner, a combination of motor-suction-unit, a casing for the motor of said unit substantially concentric with the motor shaft, an annular dirt laden air chamber surrounding said motor casing substantially concentric with the motor shaft, an upwardly impinging spring joined to the top of said casing, a dirt laden air duct longitudinally disposed above

and toward the side of said chamber in communication therewith and having a ring member rigidly joined to the top thereof, a manually removable dirt receptacle disposed at the side of said duct above said motor casing, the combined outer walls of said duct and dirt receptacle forming a middle section substantially coaxial with the shaft of said motor, a filter substantially coaxial with said motor shaft located above said air duct and said dirt receptacle and in communication therewith, a rigid sleeve surrounding said filter joined to said duct and said ring member at its bottom and to a rigid cap at the top thereof to which the operator's handle is attached, said receptacle making substantially air-tight juncture with said ring member when held upwardly by said spring.

WARD LEATHERS.
